UNITED STATES PATENT OFFICE.

SAMUEL R. SHOUP, OF WILMINGTON, DELAWARE.

VOTING-MACHINE.

No. 853,127.

Specification of Letters Patent.

Patented May 7, 1907.

Original application filed February 8, 1902, Serial No. 244,775. Divided and this application filed February 9, 1906.
Serial No. 300,322.

To all whom it may concern:

Be it known that I, SAMUEL R. SHOUP, a citizen of the United States, and a resident of Wilmington, Delaware, have invented certain Improvements in Voting-Machines, (being a division of my application filed February 8, 1905, Serial No. 244,775,) of which the following is a specification.

My invention relates to voting machines and consists of certain improvements in that class of mechanical counting mechanism whereby I am enabled to reduce the number of operative parts, facilitate the operation of registering a vote; enable a person to vote a "straight" or "cut" ticket, and "Yea" and "Nay" on special questions, and at the same time provide means to prevent fraudulent voting of any kind whatsoever; the structure being so designed that the operation of the mechanism necessary to register a vote in whole or part, locks and prevents the movement of similar mechanism for further voting until reset by the election officers.

My invention is fully shown in the accompanying drawings, in which: Figure 1, is a sectional elevation of my improved voting machine, showing the same in one position, and taken on the line *a—a*, Fig. 2; Fig. 2, is a sectional plan view, taken on the line *b—b*, Fig. 1; Fig. 3, is a sectional view on the line *a—a*, Fig. 2, of a portion of the structure, showing the position of the several parts of the mechanism after the operation of voting a straight ticket has been performed; Fig. 4, is a similar view, showing the position of the several parts of the mechanism after a cut ticket has been voted; Fig. 5, is a view similar to Fig. 1, showing part of the mechanism in diagram, and showing also the manner in which the movable parts are reset after each vote has been made; Fig. 6, is a diagrammatic plan view, taken on the line *c—c*, Fig. 1, and Figs. 7 to 10, are views illustrating details of my invention.

In the drawings, 1, 2 and 3, represent spindles arranged in rows or series and carrying knobs or handles 4 on the outside of the machine to be turned by the voter for the purpose of registering a vote. In the present instance these spindles are arranged in two sets; the main set comprising three horizontal rows of five spindles each, and the other set comprising two spindles 5 and 6, with the usual knob or handle for the "yea" and

"nay" vote on special questions, respectively.

The spindles 1 of the upper row and their co-acting mechanism are arranged to vote what is termed a "straight" ticket. In practice there will be as many operative spindles 60 as there are political parties, and each spindle, representing the full ticket of the respective parties, is to be turned a full half revolution for the purpose of registering a single vote. In like manner the spindles 2 65 and 3, are to be turned for registering a vote, but unlike the upper row they serve for sectional parts of the ticket only. As an instance of one form or arrangement of voting, the spindles 2 may actuate mechanism for 70 registering votes for the electors of the several presidential candidates, and the spindles 3, as arranged herein, are for voting for two or more candidates, as the case may be, when two or more candidates are to be voted for 75 for the same office, as, for instance, when a number of councilmen, trustees or other municipal officers of a similar character are to be voted for. The spindles 5 and 6 are employed for the "yea" and "nay" votes upon 80 special questions, and the mechanism controlled thereby is precisely similar to the mechanism operated by the other spindles.

Carried by the spindles 1, 2 and 3, as well as the spindles 5 and 6, are a series of segmental pinions 10, 11 and 12, and a notched wheel 13. The wheels 13 are each provided with two notches 14 at diametrically opposite points, and these are engaged at certain intervals by the long teeth 15 of pinions 16 85 mounted on independent spindles 17, of which there is one coacting with a registering pile carried by each of the spindles 1, 2, 3, 5 and 6, of the apparatus, said pinions 16 having in addition to the set of long teeth 15 for 90 such engagement, a set of short teeth 15^a, which, with said long teeth 15, mesh with a unit wheel 18 of the registering pile or counting mechanism arranged on or adjacent to the spindles 1, 2, 3, 5 and 6. These spindles 100 17 carry other pinions 16^a and 16^b, arranged to mesh with and operate wheels 20 and 21 of the counting mechanism employed for registering the number of votes cast. This counting mechanism is similar to that shown 105 and described in my Patent No. 694,682, dated March 4, 1902, and its special adaptation and arrangement with the other mech-

anism forms part of my pending application for patent for improvements in voting machines, before referred to.

The pinions 10, 11 and 12 I have termed 5 segmental pinions, as they may be provided with two sets of two teeth 22, as shown in Figs. 1, 5 and 6, or two sets of single teeth 22^a as shown in Fig. 7, arranged on the periphery of the same at diametrically opposite 10 points, and these teeth are adapted to engage slidable bars 23, 24 and 25 suitably guided on brackets 26 carried by the front plate of the machine. These bars are provided with sectional rack portions 27 at 15 intervals, comprising recesses arranged in sets of two forming between them a single tooth 28 for engagement with the teeth of said segmental pinions. These segmental pinions are mounted on their respective 20 spindles in various positions so that their teeth are disposed at various points with relation to each other and the teeth of the other pinions, but the racked portions of the bars 23, 24 and 25 with which these teeth 25 engage are arranged in line so that while any one of said pinions may engage any one of said bars, its time of engagement will differ from the engagement of all the other pinions with said bars. These bars are moved by 30 giving any one of the respective operating knobs or handles controlling one of the spindles a full half turn, and the actual engagement of the pinions with said bars will vary within certain limits depending upon 35 the position of the teeth of the pinions arranged to engage such special set of bars. When one of said sets of bars 23, 24 and 25 has been successively moved by such engagement it will be impossible to move another 40 bar, or, in fact, to move any of the knobs or handles on the same row, as such movement has displaced the other teeth of the bars with respect to the segmental pinions. As a 45 means of preventing accidental movement of the sliding bars, I provide spring bolts 29 mounted in boxes 30 secured to the wall of the structure and adapted to engage notches 31 in said sliding bars, when they are in the normal inactive position ready for operation.

50 The purpose of having a number of pinions and a number of bars, in most instances three, is to provide for various combinations of the co-acting parts, each of which after being actuated and causing the registration 55 of such actuation will lock the rest of the knobs or handles on the respective rows. For instance, the first spindle 1 will have its segmental pinion 10 so disposed that the teeth of the same will engage the recesses in 60 the slidable bar 23 and upon giving such knob or handles a full half turn, said bar will be moved to the left the full distance provided for to lock certain mechanism to be fully described hereinafter for preventing the turning 65 of the other knobs or handles. In the

case of the other knobs or handles of the same row, the movement of the sliding bar will displace the other racked portions of the same, bringing the plain sections of said bar opposite the teeth of the other segmental 70 pinions 10, and thereby preventing any engagement. At the same time and in proper sequence as the movement of the handle continues, the other bars 24 and 25 will be moved by the engagement therewith of the pinions 75 11 and 12 on the spindle of the knob turned; such engagement following that of the pinion 10 and moving said bars 24 and 25 the necessary distance which also brings the plain sections of said bars opposite the point where 80 the teeth of the pinions of the other spindles of the same row would engage. In diagram, Fig. 8, I have illustrated the movement of one set of these bars by the successive engagement of the several pinions 10, 11 and 85 12, carried by any one of the spindles. To prevent retraction of these bars after they have been moved and prevent the registration of another vote on the same row, as such sliding movement is designed to coat 90 with means for operating the counting mechanism one unit, I provide pawls 32 adapted to engage notches 33 in said bars after they have been moved. These pawls are carried by a vertically movable bar 34, 95 which is raised by the election officers when it is desired to reset the horizontally slidable bars 23, 24 and 25, after a citizen has registered his vote. In addition, I employ a cam bar 35 mounted adjacent to the pawl 100 carrying bar 34 and having cams 36, into the spaces between which the horizontally sliding bars 23, 24 and 25, are moved. These cams have angular faces 37, and the sliding bars are beveled at 38 so that after they have 105 engaged said cams, which means, except in the instance of the upper set of bars controlled by the spindles 1, that they have been moved the proper distance which is also sufficient to prevent the lifting of said cam 110 bar 35, they may be readily retracted by the lowering of said bar. The sliding bars controlling the straight ticket, however, instead of passing into the spaces between the cams 36 of the bar 35, engage an upper cam 39 115 carried by the same, and when said bars are moved by the operation of the spindles controlling the same, they raise said cam bar, and as the slidable bars are held by the pawls 32, the cam bar will be maintained in the 120 raised position. A series of guards 40 are disposed adjacent the cams 36, and when the cam bar 35 is raised these guards are brought in line with the other sets of slidable bars, thereby preventing movement of the same, 125 so that when a citizen registers a vote for the "straight" ticket of any one of the political parties, it will not only be impossible to vote any other "straight" ticket, but it will also be impossible to vote any sectional, part of 130

any other ticket. The bars controlling the "yea" and "nay" vote, however, are not affected by the actuation of the other parts of the machine as they may be operated after either method of voting the other portion of the ticket.

The third series of spindles, indicated at 3, in the present embodiment of my invention, carry four segmental pinions, the additional one being indicated at 12^a, and each of these pinions controls an independently slideable bar. In Fig. 6, a diagrammatic view of these bars and the pinions controlling the same is shown. In addition to the bars 23, 24 and 25, which are operated by the segmental pinions 10, 11 and 12, bars 25^a, 25^b, 25^c, 25^d and 25^e are employed, which are engaged respectively by the pinions 12^a carried by the spindles 3, the pinion 12^a on the first spindle of the row engaging the bar 25^a, the pinion 12^a on the second spindle engaging the bar 25^b, and so on. This arrangement permits voting for several candidates in such cases where two or more from a number are to be selected, as, for instance, when, as often happens in small towns, a number of councilmen or school directors are nominated, two or three only of whom are to be elected. In such case, in this arrangement of my improved mechanism, each candidate will have an independent spindle and the segmental pinions carried by said spindles and the sliding bars having recesses for engagement by these wheels, will be provided with other racked portions as desired; in the present instance an extra set 27^a is added so as to permit the operation of one or two of said spindles, whereby votes may be cast for one or two of the candidates, as the case may be. By providing the bars with other racked portions, any number of candidates may be voted by the movement of said bars, means being provided to permit the extended movement of the same. For instance in voting for two candidates, the bars 23, 24 and 25 will only be moved a certain distance by the turning of the spindle while the bar 25^a, for instance will be moved the same distance. By turning another spindle the pinions 10, 11 and 12 will engage the racked portions 27^a, moving the bars 23, 24 and 25 the same distance as before while another bar 25^e, for instance, will be moved by one of the pinions 12^a the same distance as the bar 25^a. Below the sets of spindles for voting the tickets of the several political parties in whole or part, two spindles 5 and 6 are arranged by which "yea" and "nay" votes upon special questions may be registered. These spindles carry segmental pinions for operating the slideable bars in the same manner as the other spindles, which bars are independent of the cam bar but are reset thereby in the usual manner.

In Fig. 8 I have illustrated in diagram the

manner in which the slideable bars 23, 24 and 25 are moved. Section A represents the bars at rest in the retracted position; section B shows slideable bar 23 partially moved toward the cam bar 35, representing the first part of the movement of one of the spindles carrying the segmental pinions 10, 11 and 12; section C shows slideable bar 23 fully moved and bar 24 partially moved; section D shows slideable bars 23 and 24 fully moved and bar 25 partially moved, and section E shows bars 23, 24 and 25 fully moved into engagement with the cam bar 35, a result accomplished by the engagement of the segmental pinions 10, 11 and 12, with the racks of the slideable bars, upon giving one of the spindles the full half turn required to register a vote. After each citizen has finished the operation of voting, it will be necessary to shift or reset the slideable bars and all of the mechanism controlled by or controlling the same, excepting the counting or registering mechanism, which, of course, retains the position in which it has been placed by the previous voter. For the purpose of operating this shifting mechanism, I provide the slideable plate 45, having cam slots 46 and 47 engaging pins 48 and 49; the former attached to the pawl carrying bar 34, while the latter is attached to the cam carrying bar 35. This arrangement permits independent vertical movement of the cam carrying bar, such movement being imparted when the upper set of the slideable bars controlling the "straight" votes are moved, and simultaneous movement of both bars when it is desired to reset the machine. The slideable plate 45 is under the control of the election officers, and movement of the same except as they desire, is prevented by suitable mechanism. This plate 45 may be connected in any suitable manner with a lever or other controlling means adjacent to the proper election officer, or it may be combined with the door leading to the booth so that when a voter leaves the latter the action of opening or closing the door, or both, will operate the plate 45 and reset the slideable bars.

In order that the mechanism will be ready for operating each succeeding vote, I provide means for retracting the bars to a point beyond that required for placing them in position to be acted upon by the segmental pinions 10, 11 and 12, and other means whose operation succeeds that for effecting retraction to bring the bars to the proper position for coaction by said pinions. Such action is necessary since a certain amount of lost motion must be provided for in the operation of the spindles and if attempts were made to turn a spindle after a vote had been registered, the teeth of the pinion would be displaced and not in the normal position for engagement with the racked portion of the bars.

The means for retracting the bars consist

of extensions 36^a carried by the cams 36 which serve when the cam bar is lowered to retract the sliding bars the extra distance. To return the bars, I provide a frame 50 having pins 51 disposed in cam slots 52 in the pawl carrying bar, and having the end portion 53 which lies in the same plane as the sliding bars 23, 24 and 25, ready to engage and bring them to the normal position for engagement by the segmental pinions 10, 11 and 12. This frame is retracted with the bars on the outward movement of the sliding plate 45 which raises the pawl carrying bar. On the inward movement of the plate 45, the pawl carrying bar is lowered and the walls of its cam slots acting upon the pins 51, move the frame 50 forward and with it the bars 23, 24 and 25, to the position shown in Fig. 1.

To prevent retractive movement of the spindles and the pinions and counting wheels carried thereby, pawls 55 are provided suitably mounted in the frame carrying the mechanism. These pawls engage the pinions 10. To assist the retraction of the upper set of sliding bars, as well as those of the third set to which double movement is imparted, I may employ the flat springs 56 carried by the cam carrying bar 35 and disposed in the path of said sliding bars. I may also employ the weight 57 to assist in raising the cam carrying bar after it has been lowered to retract said sliding bars.

Instead of employing segmental pinions such as those illustrated at 10, 11 and 12, with sets of two teeth, I may employ pinions such as illustrated at 10^a in Fig. 7, having teeth of enlarged size set diametrically opposite each other. The rack bars will be correspondingly recessed to receive these teeth.

To provide for the resetting of the counting wheels after the entire vote has been cast and it is desired to prepare the machine for another election or for further use, the spindles 17 carrying the pinions 16, 16^a and 16^b for operating the registering piles are supported by slidable frames 60 suitably mounted, and connected together and spaced apart by the spindles 17 which are normally positioned with said pinions in engagement with the counting wheels. These frames may be moved laterally to withdraw said pinions from such engagement and permit the wheels of the registering pile to be turned to the zero point. They are held in the engaging position by plates 61 fitting over the spindles 1, 2 and 3, which plates are fastened to the frame 60 by screws 62. The frames are suitably supported and locks are provided to prevent their movement by unauthorized persons.

My improved mechanism may be based upon a unit system, and so constructed and arranged that a frame carrying a series of spindles and the necessary mechanism can be added to the rest of the machine as desired,

it only being necessary to provide a correspondingly lengthened cam-bar and pawl-carrying bar. The machine is arranged to be accessible from one end to the other to reset the numbering or counting mechanism after the voting has finished, and at the back of the machine, I provide a door 63, preferably of metal, which covers a glass door 64 through which the numbering mechanism may be viewed and the number of votes totaled without opening the machine, although said glass door is provided with a lock and is hinged so that access to the interior of the casing may be gained by persons properly authorized.

In Fig. 10, I have shown diagrams of a series of the sets of bars 23, 24 and 25, showing their position after being moved by the several spindles. F and G respectively, represent in side elevation and plan, a set of bars in the normal inactive position, ready for operation; H, shows the effect of movement imparted by the gears on the first spindle of the machine, for instance; I, the movement imparted by the gears on the second spindle of the machine, and so on.

Although I have described the system of interlocking bars and means for operating the same in connection with a voting machine, it is obvious that the same mechanism can be applied for controlling an infinite number of mechanical devices wherein parts of the same character are arranged in series or sets, each of which may be operable singly and when operated or in operation will lock out of action or operation all of the other parts. My claims, therefore, are not limited to the mechanism of a voting machine, but are intended to cover broadly this feature of my invention.

I claim:

1. The combination of a plurality of sets of slidable elements each having engaging means, and a series of rotatable elements each having a plurality of engaging elements, each of said rotatable elements being independently capable of coacting with said engaging means to operate the slidable elements, the arrangement of the engaging elements of each rotatable element differing from all the others and the relation of the parts being such that when one of the rotatable elements is operated to actuate a set of the slidable elements the rest of said rotatable elements will be thereby locked against operation.

2. The combination of a plurality of sets of slidable elements each having engaging means, and a series of rotatable elements each having a plurality of engaging elements, each of said rotatable elements being independently capable of coacting with the engaging means on said slidable elements to operate the latter, the engaging means carried by the slidable elements serving to lock

the rest of said rotatable elements against operation when one of said rotatable elements has been operated.

3. The combination of a plurality of sets of successively slidable elements each having engaging means, and a series of rotatable elements each having a plurality of engaging elements, each of said rotatable elements being independently capable of coacting with the engaging means on said slidable elements to operate the latter successively, the engaging means carried by the slidable elements serving to lock the rest of said rotatable elements against operation when one of said rotatable elements has been operated.
4. The combination of a plurality of sets of slidable bars having engaging means, a series of rotatable spindles, and a plurality of engaging means carried by each of said spindles coacting with the engaging means of said bars to move the same, the relation of the parts being such that when one of said spindles is turned to effect the movement of the bars, the engaging means of the latter will lock the other spindles against turning.

5. The combination of two or more rotatable spindles, segmental pinions carried by each of said spindles, the arrangement of each set of pinions differing from all the others, and two or more slidable bars having notches bearing the same relation to each other, the relation of the parts being such that only one spindle may be turned at each operation and after said spindle is turned all the other spindles will be locked out of engagement with the slidable bars.

6. The combination of two or more rotatable spindles, segmental pinions carried by said spindles, and two or more slidable bars having notches, said notches bearing the same relation to each other while the pinions are disposed in different relation to each other, the relation of the coacting parts being such that only one spindle may be turned at each operation and after the turning of said spindle all the other spindles will be locked out of operative engagement with the slid-able bars.

7. The combination in a voting machine, of a set of slidable bars, a spindle, and a plurality of means one for each bar carried by said spindle for moving said bars successively.

8. The combination in a voting machine, of a plurality of sets of slidable bars having engaging means, a series of spindles, and a plurality of engaging means for said bars carried by each of said spindles, the engaging means carried by the spindles being so arranged as to move the individual bars of said sets successively.

9. The combination in a voting machine, of a casing, a series of slidable bars mounted therein, segmental pinions arranged to engage said slidable bars, said pinions being

arranged to move said bars successively, and means for turning said pinions.

10. The combination in a voting machine, of a plurality of sets of slidable bars having engaging means, and rotatable means for moving said bars, the engaging means carried by said bars serving to lock the rest of the rotatable means therefor after such movement.

11. The combination in a voting machine, of the slidable bars having a series of recesses between which teeth are formed, a spindle, means carried by said spindle and adapted to engage the teeth whereby the latter may be moved, and means for holding said bars after they have been moved.

12. The combination in a voting machine, of the slidable bars having a series of recesses between which teeth are formed, a spindle, segmental pinions carried by said spindle and adapted to engage the teeth whereby the latter may be moved, and pawls for holding said bars after they have been moved.

13. The combination in a voting machine, of a casing, a series of sliding members mounted therein, teeth carried by said members, a spindle, segmental gears thereon adapted to engage said teeth upon turning the spindle whereby the bars may be moved, a vertically movable bar engaged by the sliding bars, and means for preventing the retraction of said sliding bars.

14. The combination in a voting machine, of a series of slidable bars, a series of spindles, segmental gears carried by said spindles for actuating said bars when the former is turned, and a movable bar having slots in line with and arranged to receive said slid-able bars.

15. The combination in a voting machine, of a casing, a series of slidable bars mounted within said casing, a spindle, segmental pinions carried by said spindle and adapted to engage and move said bars, and a slotted bar to be engaged by said sliding bars when moved by the spindles.

16. The combination in a voting machine, of a casing, a series of slidable members mounted therein, teeth carried by said members, a spindle, segmental gears secured thereto adapted to engage said teeth upon turning the spindle whereby the bars may be moved, a slotted bar engaged by the sliding bars, and pawls for preventing the retraction of said sliding bars, said slotted bar being held against movement by the engagement of the slid-able bars.

17. The combination in a voting machine, of a casing, a series of sets of slidable bars mounted within said casing, a series of spindles, segmental pinions carried by each of said spindles and adapted to engage and move said sets of bars, and a slotted bar to be engaged by said sets of slidable bars when

moved by the spindles, one of said sets of sliding bars serving to raise the slotted bar and prevent the movement of the others.

18. The combination in a voting machine, 5 of a series of slidable bars, means for moving said bars, a bar having slots in line with said slidable bars, said slots having upper inclined faces and one of said faces lying in a plane to be engaged by one set of the slidable 10 bars for the purpose of raising said slotted bar.

19. The combination in a voting machine, 15 of a plurality of sets of slidable bars, means for moving said bars, a bar having slots in line with said slidable bars, said slots having upper inclined walls forming cams, the uppermost slot of said bar having its face in a plane to be engaged by the uppermost set of slidable bars when the latter are moved 20 whereby said slotted bar is raised to prevent the movement and engagement therewith of the other slidable bars, and means for depressing said slotted bar to reset the slidable bars.

25 20. The combination in a voting machine, of a plurality of sets of slidable bars, means for moving the same, a locking bar slotted to receive said slidable bars, one of said sets of bars being movable to raise said bar and thereby prevent the movement of the other bars into engagement with the slotted bar, and means for depressing the latter to reset the slidable bars.

21. The combination in a voting machine, 35 of a plurality of slidable bars, means for moving the same longitudinally, a movable bar having slots in line with said slidable bars, the slots of said bar having upper inclined walls, and means for depressing said 40 slotted bar whereby the slidable bars may be returned to their normal position, the slidable bars having beveled ends.

22. The combination in a voting machine, 45 of a plurality of slidable bars, means for moving the same successively, a slotted and movable bar to receive said slidable bars, said slotted bar when engaged by one set of said slidable bars preventing the movement of the others, means for locking the slidable 50 bars, and means for simultaneously releasing and returning said slidable bars to their original position.

23. The combination in a voting machine, 55 of a casing having a series of slidable members, teeth carried by said members, a spindle, segmental gears carried by said spindle and adapted to engage said teeth whereby the bars may be moved, a slotted bar engaged by the sliding bars, means for preventing the retraction of said slidable bars, and means for releasing the same and moving them out of the slotted bar.

24. In a voting machine, the combination 60 of the slidable bars, means for moving the same, means for holding said bars against

retraction movement when once moved forward, a slotted bar for preventing the movement of certain sets of bars after certain other bars have been moved, a bar carrying said slotted bar locking means, and means for raising said bar and the slotted bar to cause the return of the slidable bars in the resetting of the machine. 70

25. The combination in a voting machine, 75 of a series of sets of slidable bars, means for moving the same, a slotted bar, which, when engaged by one set of said sliding bars raises the same and prevents the movement of the other slidable bars, means for locking the sliding bars, and means for simultaneously 80 releasing said locking means and lowering the slotted bar whereby the slidable bars may be returned to their original position.

26. The combination in a voting machine, 85 of a plurality of slidable bars, means for moving the same longitudinally, a vertically movable bar having slots in line with said slidable bars, said slots having inclined upper walls, and a bell-crank lever for depressing said slotted bar whereby the slidable bars 90 may be returned to their normal position by the engagement of the inclined walls of the slots therewith.

27. The combination in a voting machine, 95 of a plurality of sliding bars, means for moving the same, a locking bar, which, when locked by one set of said sliding bars will prevent the movement of the others, pawls affording a supplement lock for the slidable bars, and means acting on said locking bar to simultaneously release said pawls and return the slidable bars to their original position. 100

28. In a voting machine, the combination of a plurality of slidable bars, means for moving the same, pawls for holding said bars 105 against retractive movement when once moved forward, a vertically movable locking bar for preventing the movement of certain sets of said slidable bars after the one set has been moved, a bar carrying said pawls, and means for raising said pawl bar and depressing the locking bar to effect the return of the slidable bars in the resetting of the machine. 110

29. The combination in a voting machine, 115 of a spindle, segmental gears carried by said spindle and having two sets of two teeth each, and slidable bars arranged to be moved by the engagement of the teeth of said segmental pinions.

30. The combination in a voting machine, 120 of a spindle, segmental pinions carried by said spindle, two sets of two teeth oppositely disposed on said pinions, slidable bars, and racks on said bars to be engaged by said segmental pinions. 125

31. The combination in a voting machine, 130 of a series of slidable bars, a spindle, segmental pinions mounted on said spindle, said bars having racks to be engaged by the teeth of said segmental pinions, said pinions being

capable of disposition on their spindles so as to move said bars in any order desired.

32. The combination in a voting machine, of a spindle, a series of slidable bars, segmental pinions carried by said spindle and serving to actuate said bars, a pawl carrying bar, pawls carried thereby to lock said slid-
5 able bars when once moved, a cam bar with which said sliding bars coact, an actuating
10 bar, and links connecting said actuating bar with the pawl carrying bar and the cam bar, whereby said actuating bar may cause the pawl carrying and cam bars to effect the re-
lease of and return of the slidable bars.

15 33. The combination in a voting machine, of a set of slidable bars, a spindle, means carried by said spindle for moving said bars successively, and means for preventing the accidental movement of said bars.

20 34. The combination in a voting machine, of a series of slidable bars, means for moving the same longitudinally, a bar having slots in

line with said slidable bars, the slots of said bar having inclined faces, a pin mounted on said slotted bar, and a cam plate engaging 25 said pin whereby the slidable bars may be returned to their normal position.

35. The combination in a voting machine, of a series of sliding bars, means for moving the same, a locking bar, which, when locked 30 by one of said sliding bars will prevent the movement of the others, pawls for locking the sliding bars, a plate carrying said pawls, a pin mounted on said plate, and a cam plate engaging said pin for simultaneously releasing 35 said pawls and returning the bars to their original position.

In testimony whereof, I have signed my name to this specification, in the presence of two subscribing witnesses.

SAMUEL R. SHOUP.

Witnesses:

HENRY HORNATIN,
JOHN STELJES.
